(57) **CLAIM**

The ornamental design for a scalloped implantable injectable port, as shown and described.

DESCRIPTION

FIG. 1 is a perspective view of a scalloped implantable injectable port according to the present invention.

FIG. 2 is a top plan view thereof.

FIG. 3 is a bottom plan view thereof.

FIG. 4 is a left side elevation view thereof.

FIG. 5 is a right side elevation view thereof.

FIG. 6 is a front elevation view thereof; and,

FIG. 7 is a rear elevation view thereof.

Any broken line illustration of environmental structure in the drawing is not part of the design sought to be patented.

Our scalloped implantable injectable port is a medically implantable device having a port that has characterized by a port housing with scalloped edges and the written expression “scalloped implantable injectable port”.
